UNITED STATES PATENT OFFICE.

JOSEPH DAIN, OF MOLINE, ILLINOIS, ASSIGNOR TO DAIN MANUFACTURING COMPANY OF IOWA, OF OTTUMWA, IOWA, A CORPORATION OF IOWA.

HAY-PRESS.

1,147,710.

Specification of Letters Patent. Patented July 27, 1915.

Application filed July 11, 1914. Serial No. 850,453.

To all whom it may concern:

Be it known that I, JOSEPH DAIN, a citizen of the United States, and a resident of Moline, in the county of Rock Island and State 5 of Illinois, have invented certain new and useful Improvements in Hay-Presses, of which the following is a specification, reference being had to the accompanying drawings.

10 My invention relates to hay presses of the gear-driven type, and has particularly to do with presses in which the plunger is operated by a drive-gear, or pair of gears, eccentrically mounted and driven from a 15 suitable source of power by a single reducing pinion, or pair of reducing pinions, in such manner as to reduce the speed and thereby increase the power of the plunger during the compression stroke and to increase the speed of the plunger on the 20 return stroke. An example of this general type of press is shown and described in my pending application Serial No. 721,354, filed September 20, 1912. In the latter press the 25 eccentrically-mounted driving gears—a pair of which is provided in order to equalize the strain—are mounted in fixed bearings, and the pinions by which power is communicated to them from the source of power, 30 which is preferably an internal combustion motor mounted on the frame of the press, are mounted in bearings carried by a support which swings to compensate for the eccentricity of the driving gears. These 35 pinions are driven by means of a pulley and belts operated by the motor, and it is necessary to provide means to maintain the proper tension on the belts as the pinions swing back and forth.

40 My present invention has for one of its objects to provide a construction in which the driving pinions will be mounted in stationary bearings, thus avoiding the necessity of employing variable means for maintaining the tension of the belts.

Another object is to relieve the eccentric gear bearings from the pressure of the plunger on its operative stroke.

A further object is to provide certain improvements in the construction of presses of this character, as hereinafter set forth.

I accomplish these objects as illustrated in

the drawings and as hereinafter described. That which I believe to be new will be set forth in the claims.

55 In the accompanying drawings, Figure 1 is a side elevation of the principal parts of my improved hay press; Fig. 2 is an enlarged detail, being a partial longitudinal section of the driving mechanism and some 60 of the connected parts, said section being taken on line 2—2 of Figs. 4 and 5; Fig. 3 is a similar view, being a partial longitudinal vertical section on line 3—3 of Fig. 5; Fig. 4 is a plan view of the parts shown in 65 Fig. 2; Fig. 5 is a partial horizontal section on line 5—5 of Fig. 2; Fig. 6 is a detail, being a perspective view illustrating one of the 70 shoes which control the reciprocatory movement of the eccentric drive-gears, and the 75 bracket which supports it; and Fig. 7 is an enlarged detail, being a partial plan view illustrating the manner in which the eccentric drive-gears are mounted so as to be capable of moving longitudinally of the 75 frame of the press.

Referring to the drawings, 8 indicates the usual press frame, which is provided with a baling chamber supplied through a hopper 9, said frame being mounted on wheels 10.

80 11 indicates an internal combustion motor suitably mounted on the frame of the press, near one end thereof, and operating to drive pulleys 12 from which the compression mechanism is actuated.

85 13 indicates the usual fly-wheels.

14 indicates a drive-shaft, which is mounted in suitable bearings carried by plates 15 secured to the frame of the press, as shown in Fig. 1, said bearings being 90 fixedly mounted. The shaft 14 carries pulleys 16, which are driven from the pulleys 12 by belts 17, as shown in Figs. 1, 4 and 5.

18 indicates pinions mounted on the shaft 14 and keyed thereto so as to rotate there- 95 with.

19 indicates a pair of drive-gears which mesh with the pinions 18 and are provided with eccentrically-disposed axes 20 mounted in bearings 21 carried by bearing-plates 22 100 mounted at opposite sides of the press frame, as shown in Figs. 1 and 5. Said plates 22 are movable longitudinally of the frame of the press so as to be capable of reciproca-

tion, and in order to hold them properly in position and to facilitate their reciprocatory movement, each plate 22 has associated with it a plate 23 disposed at the opposite 5 side of the members of the press frame 8. The plates 22-23 are held a fixed distance apart by spreaders 24 and may be freely reciprocated between the pairs of angle-irons composing the press frame, the outwardly- 10 projecting limb of the angle-irons forming ledges or supporting bearings for the plates 22 and upon which they move.

In order to hold the gear axes 20 properly in position in their respective bearings, the 15 hub of each gear 19 is provided with an annular flange 25 which abuts against the inner face of the appropriate bearing 21, as shown in Fig. 5, and on the outer face of each gear axis 20 is provided a plate 26 20 which is secured to the axis 20 by a bolt 27, the inner end of which is hooked into a perforated lug 28, as illustrated in Fig. 5. Thus the axes 20 cannot become displaced, but may readily be removed by removing 25 the nuts on the bolts 27 and disconnecting the plates 26.

Each of the gears 19 is provided with an annular flange 29 disposed laterally with reference to the toothed portion of its periphery, as best shown in Fig. 5, this flange forming an annular shoulder or rail which transmits the end thrust of the plunger to suitable rollers 30 mounted on the drive-shaft 14, as best shown in Fig. 5. Thus the 30 compression strain is not sustained by the bearings of the eccentrically-mounted drive-gears, but is sustained by the rollers 30 and through them is transmitted to the bearings 35 of the drive-shaft 14.

40 31 indicates steel plates which are fitted to those portions of the gears 19 which bear upon the rollers 30 during the compression stroke of the press. These plates are provided at the points on the flanges 29 where 45 the greatest compression strain occurs, so that it will be unnecessary to renew the entire gears on account of wear, but they may be restored to their original condition by simply renewing the wearing plates 31 as occasion 50 requires.

32 indicates the plunger or pitman by which the hay is compressed in the compression chamber, said plunger having an operating head 33, as shown in Fig. 3. The 55 plunger extends back between the eccentrically-mounted drive-gears 19 and is connected to a wrist-pin 34 pivotally connected with said drive-gears in such manner that the plunger will be operated with the greatest 60 power and at the slowest speed on the compression stroke and with the greatest speed and the least power on the return stroke, as illustrated in Fig. 2.

Owing to the eccentric mounting of the 65 drive-gears 19 and the fact that the drive-

shaft 14 is mounted in stationary bearings, it will be apparent that in order to maintain the drive-gears 19 in mesh with the pinions 18 the bearings of said drive-gears must be reciprocated as the gears rotate and that 70 means must be provided for holding said gears in mesh with the pinions 18. To this end I provide curved shoes 35 which are preferably made of angle-iron, as shown in Fig. 6, and are adapted to bear on the inner 75 surfaces of the peripheral portions of the gears 19, said gears being provided with annular shoulders 36 for that purpose, as shown in Fig. 5. The curved shoes may be provided with anti-friction rollers, if desired. The shoes 35 are carried by brackets 37 having collars 38 adapted to fit upon bearings 38^a formed upon the plates 15, as shown in Figs. 5 and 6, and preferably the shoes 35 are adjustably connected with the brackets 37 by bolts 39 fitted in slots 40 in the brackets 37 so that the shoes may be adjusted to compensate for wear. It will be evident 80 from the foregoing that the shoes 35 will constantly hold the gears 19 in mesh with the pinions 18 and consequently will cause the axes 20 of said gears and the bearings in which they are mounted to reciprocate in the frame of the press to allow for the maintenance of such engagement of the gears. Of course, when the bearings 21 move toward the compression chamber, which occurs on the compressing stroke of the plunger, the shoes 35 are idle as far as performing any 90 function is concerned, but on the return stroke of the plunger said shoes act to pull the bearings 21 to the right as the gears 19 rotate. This, however, does not impose much strain on the shoes as it occurs on the idle stroke of the plunger, as above stated. 95 As the compression strain is transmitted through the structure of the drive-gears to the rollers 30 and is not sustained by the axes or bearings of said drive-gears, there is very little wear on such bearings. The 100 shoes 35 may readily be removed and renewed by simply disconnecting the bolts 39. 105

It will be noted that as the axes of the drive-gears 19 move toward the compression chamber on the compressing stroke of the plunger, the desired length of plunger stroke may be secured with the wrist-pin 34 comparatively close to the axes of the gears, thereby gaining an increased leverage of the drive-gears upon the plunger. A further 110 advantage of mounting the wrist-pin near the axis of the gears is that there is less angularity of the pitman when the pitman is traveling over the axis on the compression stroke, since by my present construction the path traveled by the wrist-pin does not describe a true circle but an ellipse, due to the fact that while the wrist-pin travels about the gear axis, as the axis moves it elongates 115 the path of the wrist-pin travel so that the 120 125 130

wrist-pin describes an ellipse instead of a circle.

41 indicates the usual rocking beater-arm, which is mounted upon a pivot 42 and is connected by a bar 43 to the wrist-pin 34 so that it is automatically operated in the usual way.

So far as I am aware, I am the first in the art to operate a plunger by connecting it with gears mounted eccentrically, the axes of which are arranged to reciprocate toward and from the compression chamber; also to operate such gears by pinions mounted on stationary bearings; and also to provide rollers arranged to take the end-thrust of the compression. These features, therefore, are claimed broadly.

That which I claim as my invention, and desire to secure by Letters Patent, is,—

20 1. A press, comprising a compression chamber, a plunger, an eccentrically-mounted gear connected with said plunger for operating the same, a bearing for said gear movable toward and from the compression chamber, and means for rotating said gear and simultaneously moving it toward and from the compression chamber.

30 2. A press, comprising a plunger, an eccentrically-mounted rotary drive-gear connected with the plunger and mounted in movable bearings, and means for rotating said drive-gear.

35 3. A press, comprising a plunger, an eccentrically-mounted rotary drive-gear connected with the plunger and mounted in movable bearings, and a pinion mounted on stationary bearings for rotating said drive-gear.

40 4. A press, comprising a plunger, an eccentrically-mounted rotary gear connected with said plunger, reciprocating bearings for said drive-gear, and means for rotating said gear.

45 5. A press, comprising a plunger, an eccentrically-mounted rotary gear connected with said plunger, reciprocating bearings for said drive-gear, and means for rotating and reciprocating said gear.

50 6. A press, comprising a plunger, an eccentrically-mounted gear connected with said plunger, reciprocating bearings for said drive-gear, and a pinion mounted in stationary bearings and meshing with said drive-gear for rotating the same.

55 7. A press, comprising a plunger, an eccentrically-mounted gear connected with said plunger, reciprocating bearings for said drive-gear, and means for reciprocating said gear.

60 8. A press, comprising a plunger, an eccentrically-mounted drive-gear connected with said plunger, said drive-gear having bearings adapted to reciprocate with the plunger, a drive-shaft, means associated with said drive-shaft for reciprocating the

gear, and a pinion mounted on said drive-shaft and meshing with said gear for rotating the same.

65 9. A press, comprising a plunger, an eccentrically-mounted drive-gear connected with said plunger and adapted to reciprocate therewith, a stationary shaft, a pinion mounted on said shaft and meshing with said gear, means for reciprocating the drive-gear, a pulley mounted on said shaft, and a belt for driving said pulley.

70 10. A press, comprising a plunger, an eccentrically-mounted drive-gear connected with said plunger, means for rotating said gear, and a thrust-bearing co-operating with said gear to take the compression thrust.

75 11. A press, comprising a plunger, an eccentrically-mounted drive-gear connected with said plunger, and a roller bearing against an annular portion of said gear and arranged to take the compression thrust thereof.

80 12. A press, comprising a plunger, an eccentrically-mounted drive-gear, a pinion meshing with said gear for rotating the same, and a roller bearing against an annular portion of said gear for taking the compression thrust thereof.

85 13. A press, comprising a plunger, an eccentrically-mounted gear connected with said plunger, said gear being adapted to reciprocate with the plunger, a stationary shaft, a pinion mounted on said shaft for driving said gear, and a roller mounted on said shaft and bearing against an annular portion of said gear for taking the compression thrust thereof.

90 14. A press, comprising a plunger, an eccentrically-mounted gear connected with said plunger, said gear being adapted to reciprocate with the plunger, a stationary shaft, a pinion mounted on said shaft for driving said gear, a roller mounted on said shaft and bearing against an annular portion of said gear for taking the compression thrust thereof, and means associated with said shaft for reciprocating said gear.

95 15. A press, comprising a plunger, an eccentrically-mounted gear connected with said plunger, said gear being adapted to reciprocate with the plunger, a stationary shaft, a pinion mounted on said shaft for driving said gear, a roller mounted on said shaft and bearing against an annular portion of said gear for taking the compression thrust thereof, and a shoe mounted on said shaft and engaging an annular portion of said gear for holding said gear in mesh with said pinion.

100 16. A press, comprising a plunger, an eccentrically-mounted gear connected with said plunger, said gear being adapted to reciprocate with the plunger, a stationary shaft, a pinion mounted on said shaft for driving said gear, and a shoe mounted on

said shaft and engaging an annular portion of said gear for holding said gear in mesh with said pinion.

17. A press, comprising a frame, a plunger, an eccentrically-mounted gear connected with said plunger for reciprocating the same, reciprocating bearings for said gear mounted in said frame, a shaft mounted in

stationary bearings, a pinion mounted on said shaft and meshing with said gear, and means connected with said shaft for holding said pinion in mesh with said gear.
